HANDLEBAR GRIP

Sid Corlin, 6125 N. Talman Ave., Chicago, Ill.

Filed May 20, 1964, Ser. No. 80,071

Term of patent 14 years

(Cl. D90—11)

Fig. 1

Fig. 2

Fig. 3

Fig. 4

FIG. 1 is a side elevational view of a handlebar grip showing my new design;

FIG. 2 is a top plan view thereof;

FIG. 3 is a left end view thereof; and

FIG. 4 is a right end view thereof.

The fragmentary portion of a handlebar shown in broken lines in FIG. 1 is included for illustrative purposes only.

I claim:

The ornamental design for a handlebar grip, as shown and described.
